UNITED STATES PATENT OFFICE

172,336

TOBACCO CURER

Jerry Allen Burke, Jr., Richmond, Va.

Application October 27, 1953, Serial No. 27,340

Term of patent 14 years

(Cl. D85—7)

To all whom it may concern:

Be it known that I, Jerry Allen Burke, Jr., have invented a new, original, and ornamental Design for a Tobacco Curer, of which the following is a specification, reference being had to the accompanying drawing, forming a part hereof.

Fig. 1 is a perspective view of a tobacco curer embodying my new design;

Fig. 2 is a similar view looking in a direction substantially at right angles to that of Fig. 1; and

Fig. 3 is a fragmentary vertical section substantially on the line 3—3 of Fig. 1, looking in the direction of the arrows.

I claim:

The ornamental design for a tobacco curer, as shown.
